UNITED STATES PATENT OFFICE.

JOHN R. PRICE, OF NEWARK, NEW JERSEY.

CARBURETER.

944,048.

Specification of Letters Patent. Patented Dec. 21, 1909.

Application filed February 26, 1906. Serial No. 302,968.

To all whom it may concern:

Be it known that I, JOHN R. PRICE, a citizen of the United States, residing at Newark, in the county of Essex and State of New Jersey, have invented a new and useful 5 Carbureter, of which the following is a specification.

The objects of this invention are to provide an improved carbureter particularly 10 adapted for use with motors for driving automobiles; to secure a mixture of gasolene and air which shall be of substantially uniform quality or degree of richness; to regulate for this purpose the admission of air 15 to the mixing chamber; to effect such regulation automatically, and independent of the throttle; to secure a simple construction, and one which can be adapted to carbureters already in use, and to obtain other advantages and results as may be brought out in 20 the following description.

The invention consists in the improved carbureter, substantially as will be herein-after described and finally set forth in the 25 claims.

Referring to the accompanying drawings, in which like numerals of reference indicate corresponding parts in each of the several figures, Figure 1 is a vertical central sectional view of my improved carbureter, shown entire with a float chamber or constant level device for the gasolene feed; Fig. 30 2 is a cross-section upon line α , Fig. 1; Fig. 3 is a view of the vaporizer, partly in central 35 vertical section, looking in a direction at right angles to that of Fig. 1; Fig. 4, is a plan of the vaporizer, and Fig. 5 is a cross-section as on line γ , Fig. 3, with the throttle almost entirely closed, and a certain partition and screens removed.

In said drawings, 1 designates a float chamber, having a float 2 therein controlling an inlet valve 3, coöperating with a valve seat 4 in the bottom of the tank. The valve 45 seat 4 communicates with a supply connection 5, which may be attached to any suitable reservoir or other means, (not shown), of feeding gasolene to the chamber 1. At the bottom of the connection 5 is a drain 50 cock 6, and extending from the chamber 1 is a feed pipe 7, with an upwardly directed ex-

tremity 8, from which the gasolene passes into the vaporizing chamber. All the parts thus far described are old in the art, and it is in the vaporizer, next to be described, that my invention particularly inheres. Said vaporizer comprises a body portion or casing 9, with a cylindrical interior in which fits a rotatable throttle tube 10, preferably formed of sheet metal. A cover 11, secured to the top of the body portion 9, overlies the edges 12, of the upper open end of the throttle tube 10, and is segmentally cut away for a part of its periphery, as at 13, to accommodate a handle piece 14, fixed to the said 65 throttle tube.

At the upper part of the body portion 9, is a lateral throttle opening or outlet 15, from which a tube or connection (not shown) may lead to the motor, and the throttle tube 10, has a corresponding port 16, adapted to be turned into or out of coincidence with the said opening 15. Preferably this port 70 16, is pear-shaped, with its small end 17, extending rearwardly as the tube 10 is 75 turned to close the throttle, so as to enable finer adjustment in closing.

At the bottom 18, of the throttle tube is a central depending extension 19, which receives the extremity 8, of the feed pipe 7, 80 and forms an annular air passage or inlet around the same. At one side of said air inlet 19, a sector of the throttle-tube floor is cut away as at 20, and in the bottom of the casing 9, is a similar opening 21, the relation of said apertures to each other and to the throttle port 16, being such that when the throttle outlet 15, is nearly closed, they coincide to permit an auxiliary air supply 85 to the mixing chamber. As soon as the 90 throttle starts to open, however, the said auxiliary air opening is closed, and remains so.

To provide an auxiliary air supply when the throttle is open, I mount upon the cover 95 11, of the vaporizing chamber 9, a valve adapted to be automatically governed in its movements to admit air to the vaporizing chamber, by the suction of the motor. In construction, the cover 11, has an aperture 100 which is tapped to receive an exteriorly threaded sleeve 22, providing at its bottom

a valve-seat 23, facing the vaporizing chamber. A valve 24, normally engages the said seat 23, and has a stem 25, projecting away from the vaporizing chamber in the said sleeve 22. Furthermore, the said sleeve 22, has near its valve seat 23, arms 26 which project radially inward and support a tubular sheath 27, inclosing the valve stem 25. The sleeve 22, has also its interior threaded, and an inner sleeve 28, screws into said outer sleeve 22, furnishing at its upper part an interior slideway for a piston 29, upon the end of the valve stem 25. The inner end of said inner sleeve 28, has arms 30, extending radially inward and supporting an annular spring seat 31, around the valve stem sheath 27. A co-operating spring cap 32, is adjacent to the piston 29, and between said spring seat 31, and spring cap 32, are arranged spiral springs 33, 34, one inside the other, and one, preferably the outer one 34, being lighter and slightly longer than the inner one 33. Obviously, therefore, when the valve 24, is opened by the suction of the motor, it opens against the one or both of the springs 33, 34, and the tension of said springs, and thus the opening of the valve, can be regulated by screwing the inner sleeve 28, in the outer sleeve 22. When the outer light spring 34, alone engages the cap 32, the valve will open very easily, but by increasing the tension of said spring, and by bringing the stiff spring 33, into play, a much less sensitive action of the valve is obtained, as may be desired. The automatic admission of air can thus be regulated.

For ingress of air, the sleeves 22 and 29, have each a circumferential series of apertures, 35 or 36, the number of openings in the two sleeves differing, as six in one and seven in the other, so as to insure the registration of at least a portion of them, irrespective of the adjustment of the springs, as shown in Fig. 2. Such adjustment is slight in the direction of the length of the sleeves, and the holes 35, 36, are easily made large enough so that they will not be carried past each other.

A cap 37, closes the outer end of the inner sleeve 29, having a vent 38, so as to not unduly restrict movement of the piston 29, and yet secure a cushioning of the same to prevent its pulsation under the suction of the motor. Jam rings 39, 40, upon the inner and outer sleeves 29, 22, respectively, serve to lock them in place when adjusted.

I have shown depending from the cover 11, into the vaporizing chamber, a flaring funnel-like air guide 41, which has its contracted end closely around the end of the outer sleeve 22, which projects into the vaporizing chamber. Downwardly contracting frusto-conical screens 42, 42, are also shown arranged in the lower part of the throttle tube 10, to afford evaporating sur-

face for the gasoline, and, lastly, at about the level of the lower part of the throttle port 16, is a substantially horizontal partition 43, with a crescent-shaped recess 44, in the edge thereof adjacent to the said throttle port. This partition may be employed to divide the suction of the motor to operate both on the gasoline supply at the bottom and the auxiliary air supply at the top, of the vaporizer, and in any desired proportion.

In operation, the air inlet valve having been suitably adjusted, it will be seen that with the throttle open only just enough to keep the motor running, as shown in Fig. 5, the air-inlet at the bottom of the vaporizer is open so as to admit air, and obviously at this time there is not enough suction to operate the inlet valve at the top of the vaporizer. As the throttle is opened further, the auxiliary inlet at the bottom of the vaporizer is closed, and the said valve at the top comes into play automatically. Furthermore, since the said valve operates by the suction, regardless of the throttle position, it will be understood that the auxiliary air supply may diminish without any closing of the throttle, as for instance when an automobile encounters a hill or the load upon a motor is otherwise increased.

The function of my auxiliary air inlet at the bottom of the throttle tube is to vary the air inlet independently of the automatic valve, or at such times as the said automatic valve is not in operation, as for instance when the motor is running with the throttle nearly closed and there is not enough suction from the engine to operate the automatic valve. Under these conditions, the mixture may be too rich, as only minimum power is wanted, and the simplest way to secure a weaker mixture is by increasing the air inlet at the bottom of the throttle tube, and thus both diluting the gasoline fed and also reducing the feed by reducing the suction on it. This result is accomplished by the means I have shown and described, viz., auxiliary air inlet means adapted to open as the suction of the engine decreases and to close as the suction of the engine increases. When the throttle is nearly closed, the auxiliary air inlet is opening and thereby reducing the gasoline feed suction as well as diluting the mixture. When the throttle is opened again, the auxiliary air inlet closes, thus giving the maximum gasoline feed, and the usual or upper auxiliary air valve is operated by the engine suction to regulate the supply of air to the mixture.

While the detail mechanical construction of my invention can be varied, I prefer a construction such as I have shown which can be applied to many carburetors already in use by simply forming a central screw-

threaded opening in the top, and recessing its edge to provide for turning the throttle tube.

Having thus described the invention what

5 I claim as new is:

1. In a carbureter, a vaporizing chamber casing having a lateral throttle opening, a bottom central aperture and an auxiliary air inlet, a rotatable throttle tube fitting said 10 casing and having an extension fitting the bottom aperture, said tube having ports one adapted to turn into coincidence with the auxiliary air inlet as the other passes out of registration with the throttle opening, a 15 cover for the vaporizing chamber casing provided with air inlet means adapted to be automatically operated by suction through the throttle, and a gasolene feed tube in the said throttle tube extension providing a sur- 20 rounding air space.

2. In a carbureter, a vaporizing chamber casing having a lateral throttle opening and a lower auxiliary air inlet, a throttle tube fitting said casing and having ports one 25 adapted to turn into coincidence with the auxiliary air inlet as the other passes out of registration with the throttle opening, a cover for the casing segmentally recessed or cut away at its periphery to expose the upper edge of the throttle tube, handle means upon said exposed portion of the throttle tube for turning the same, air inlet means upon the said cover adapted to be operated by suction through the throttle, and gaso- 30 lene feed means.

3. The combination with a carbureter body portion having a throttle and gasolene feed means, of a sleeve mounted in said body portion and being interiorly threaded 40 and forming at its inner end a valve seat, an inner sleeve screwing within said outer sleeve, a valve for said valve seat having a stem provided with a head slidably fitting the inner sleeve, and a spring supported 45 at one end on said inner sleeve and adapted to engage said valve to seat the same, said sleeves forming an air inlet to the carbureter controlled by said valve.

4. The combination with a carbureter 50 body portion having a throttle and gasolene feed means, of a sleeve mounted in said body portion and being interiorly threaded and forming at its inner end a valve seat, an inner sleeve screwing within said outer sleeve, a valve for said valve seat having a stem pro- 55 vided with a piston head fitting the inner sleeve, a cap upon the end of said inner sleeve adapted to confine the air and form a cushion for said piston, and a spring supported 60 at one end on said inner sleeve and adapted to engage said valve to seat the same, said inner and outer sleeves having between the said valve and its piston head apertures for the admission of air.

65 5. The combination with a carbureter

body portion having a throttle and gasolene feed means, of a sleeve mounted in said body portion and being interiorly threaded and forming at its inner end a valve seat, an inner sleeve screwing within said outer 70 sleeve, a valve for said valve seat having a stem provided with a piston head fitting the inner sleeve, a cap upon the end of said inner sleeve adapted to confine the air and form a cushion for said piston, and a spring 75 supported at one end on said inner sleeve and adapted to engage said valve to seat the same, the said outer and inner sleeves having between the piston and the carbureter body portion circumferential series of 80 holes in their walls, unequal in number, and some of which always register.

6. The combination with a carbureter body portion having a throttle and gasolene feed means, of a sleeve mounted in said 85 body portion and being interiorly threaded and forming at its inner end a valve seat, an inner sleeve screwing within said outer sleeve and forming at its inner end a spring seat, a valve for said valve seat having a 90 stem provided with a head slidably fitting the inner sleeve, said sleeves forming an air inlet to the carbureter controlled by said valve, and springs one within the other surrounding the valve stem between the said 95 spring seat and valve stem head, one of said springs being heavier and shorter than the other.

7. A carbureter having a casing with a main bottom air inlet, an auxiliary bottom 100 air port and a lateral throttle opening, a throttle tube rotatably disposed in the casing and provided with a segmental slot in its bottom adapted to coöperate with the said auxiliary air port and also with a side opening adapted to coincide with the lateral port of the casing, said slot adapted to move into coincidence with the auxiliary air inlet as the side opening of the throttle tube moves out of registration with the throttle opening of the casing and vice versa, means for feeding gasolene into the body of the carbureter through said main bottom opening, and an automatically operating auxiliary valve arranged on the carbureter to admit 105 air to the latter and controllable solely by the suction and speed of the motor to which the carbureter is connected.

8. In a carbureter, the combination of a body portion providing a vaporizing chamber, a main air inlet, a mechanically operated auxiliary air inlet and an automatically operated auxiliary air inlet for admitting air to said chamber, a discharge leading 110 from said chamber, a throttle for said discharge, and means for restricting the said mechanically operated auxiliary air inlet by opening of the discharge and opening 115 said mechanically operated auxiliary air inlet by restricting of the discharge. 120

9. In a carbureter, the combination with a vaporizing chamber having a main air inlet, gasoline feed means, and a throttle controlling the discharge from said chamber,
5 of two auxiliary air inlets to said chamber independent of each other, one of said inlets adapted to open as the suction of the motor

through the carbureter increases, and means for restricting the other auxiliary air inlet by opening of the throttle.

JOHN R. PRICE.
